(57) **CLAIM**

The ornamental design for a console with hand controls for telescopic lifter, as shown and described.

DESCRIPTION

FIG. 1 is a front-top perspective view of a console with hand controls for telescopic lifter, showing the new design; FIG. 2 is a front-left side-top perspective view thereof; and, FIG. 3 is a front-right side-top perspective view thereof. The broken lines in the drawings illustrate unclaimed environmental structure and form no part of the claimed design.

1 Claim, 3 Drawing Sheets
